INVENTOR
GEORGE A. HOYEM

BY ATTORNEYS

UNITED STATES PATENT OFFICE.

GEORGE ARTHUR HOYEM, OF LENNEP, MONTANA.

CLEANING IMPLEMENT.

Original application filed September 28, 1921, Serial No. 503,904. Divided and this application filed May 9, 1923. Serial No. 637,832.

To all whom it may concern:

Be it known that I, GEORGE ARTHUR HOYEM, a citizen of the United States, and a resident of Lennep, in the county of Meagher and State of Montana, have invented a new and Improved Cleaning Implement, of which the following is a full, clear, and exact description.

This invention relates to a cleaning implement and aims to provide a device of this nature more particularly adapted for use in connection with the cleaning of carbon deposits from spark plugs.

One of the principal objects of the invention is to provide a device as just characterized, having essentially a brush-type working end of a peculiar nature; and a particular object of the invention, in this connection, is to provide such a working end which shall be especially useful, as I have found in practice, when used either before or after the application of a cleaning device for scraping out the internal surfaces of the spark plug.

Such a scraping device is described and claimed in my U. S. Letters Patent No. 1,461,904, of July 17, 1923, of which the present application is a division; and in that application there is disclosed, but not claimed, the brush-type working end for a spark plug cleaning device as herein claimed as well as disclosed.

A further object is to provide a brush or bristle structure, itself of an inherently resilient type, to cooperate with the preferably slightly stiffer resilient support for the brush structure afforded by said handle, thereby to provide a cleaning device of the brush or bristle carrying type adapted to be applied to the interior of a spark plug with maximum efficiency and a minimum amount of brushing manipulation.

Still further objects of the invention, and the invention itself will be better understood from the following description, when taken in connection with the accompanying drawing illustrating, but merely by way of example, one practical embodiment of the invention.

In said drawing—

Figure 1 is a perspective view of a cleaning implement embodying my improved construction and showing the same in use;

Figure 2 is a similar perspective view

showing all of the parts of the cleaning implement, and

Figure 3 is a transverse sectional view taken along the line 3—3 and in the direction of the arrows indicated in Figure 2.

The numeral 5 indicates the body of the implement, which is in the nature of a metal sleeve or elongate hollow handle, the end portions of which handle are extended to provide two pairs of legs 6 and 7. It will be understood that by this construction each one of both pairs of legs will incorporate a certain amount of resiliency when pressed to converge toward the other leg of its pair.

Referring now to the parts of the device claimed in my said co-pending application, and hence not claimed here, it will be seen that the outer ends of legs 7 are enlarged into heads 8 presenting rounded faces carrying scraper or blade elements 10 formed by striking out portions of such heads. As the cleaning device is shown applied in Figure 1, the same has its scraper end inserted in the sparking chamber of a spark plug 9; say with the cleaner at rest after the conclusion of a back and forth rotation of the scraper end thereof in the plug, sufficient to complete a scraping operation found to be a desirable preliminary to the application of the brush end of the cleaner to the interior of the spark plug.

Referring now to the features of construction of the unitary implement of Figure 2 having a special relation to the invention of the present application, it will be seen that legs 6 have their outer ends 12 bent upon themselves; this being a preferable construction for mounting a brush element for projection beyond the free end of each leg, it being understood, however, that such elements may be secured in any desired manner.

Now examining the brush elements, it will be seen that each preferably comprises a single length of a previously known type of resiliently flexible twisted bristle carrying wire. The single wire here constituting each brush element is reversely bent a plurality of times so as to form substantially the letter W and to present mutually converging terminal portions for anchorage by the bent over terminal portion 12 of a leg 6.

In operation, it will, of course, be under-

2
stood that on reversing the body or handle 5 from the position shown in Figure 1 and inserting the brush end of the implement into the interior of plug 9, in such a way that 5 ground electrode 9^a of the plug is straddled by legs 6, back and forth partial rotations of the implement will effectually clean out 10 all previously loosened carbon deposits, as deposits loosened by a preliminary application of the scraper end of the implement.

It has been found in practice that very few such rotations of the implement, rapidly performed, satisfactorily frees the plug of 15 all carbon deposits which would otherwise have a deleterious effect on the operating efficiency of the engine carrying the plug. It is pointed out that by virtue of the peculiar construction of the brush elements themselves and of the coacting parts of the 20 implement, it would be practically impossible for any of the loosened carbon deposits to settle into parts of the implement in such a way as to interfere with the cleaning efficiency thereof, or in such places thereon or 25 therein as to make it difficult thoroughly to clean the implement after the latter has been applied to clean a plug. It will also be seen that the peculiar brush element provided is 30 of such a construction as to preclude any carbon deposits from eluding secure trapping by the brushing end of the implement.

Variations may, of course, be resorted to within the scope of the following claims.

I claim:

35 1. As a new article of manufacture, a

cleaning implement for spark plugs including a handle portion, and a cleaning element offset from said handle portion, said element comprising an elongate bristle carrying member, said element being reversely bent on itself in its bristle carrying portion.

2. As a new article of manufacture, a cleaning implement for spark plugs including a handle portion, and a cleaning element 40 offset from said handle portion, said element comprising an elongate bristle carrying member, said element being a twisted wire bristle carrying member bent on itself and anchored at its opposite ends to the handle portion, the handle portion carrying a reduced resilient terminal portion to which 45 said element is so anchored.

3. As a new article of manufacture, a cleaning implement for spark plugs including a pair of legs resiliently connected, and cleaning elements carried by the legs, such elements comprising a plurality of bristle carrying members, said legs being carried at opposite sides of one end of an elongate 50 handle formed of sheet metal, thereby to permit shaping of the opposite end portions of the handle into scraper elements.

4. A cleaning implement, including a sleeve, legs extending from the ends of said sleeve, and brushes attached to said legs, one brush on each leg, each brush formed into a substantially W-shaped body portion.

GEORGE ARTHUR HOYEM.
